WEB-FEEDING MECHANISM

Arthur Thomas, Wallington, England, assignor to
 Powers Accounting Machines Limited, London,
 England, a British company

Application February 2, 1944, Serial No. 520,835
 In Great Britain February 5, 1943

22 Claims. (Cl. 164—112)

This invention relates to apparatus for feeding tape, strip, or web record material, e. g., paper or any material of small or greater strength, through a punching or a sensing machine by means of feeding pins engaging feed holes in the web, which pull the web through the machine, and is particularly applicable to apparatus for feeding paper tape intended to be punched by selective code-holes and feed holes to be used for controlling statistical or accounting machines.

A main object of the invention is to provide an improved construction of mechanism for engaging and disengaging the feed pins and feed holes and a further object is to provide an improved form of the above mentioned kind of feeding mechanism in which the tension in the record material, while it is being fed, is reduced to a minimum and the accuracy of the feed thereby increased.

According to the present invention mechanism for feeding tape, strip, or web material, e. g., weak or stronger paper, through a machine includes in combination feeding pins carried on a support movable to and fro to feed the web intermittently, and means for moving the web relatively to the pins at each end of the stroke of the support so as to effect engagement of the feed holes in the web with the pins at the beginning of a feed stroke of the support and disengagement of the holes from the pins at the end of the feed stroke.

Preferably according to the invention the pins are mounted on the end of a hinged element and mechanism is provided for rocking said hinged element about its hinge axis between successive movements of the web relatively to the pins.

According to a further feature of the invention the mechanism may include a pair of elements movable with the support and disposed to embrace between them the portion of the web which is in the region of the pins, together with mechanism operating in timed relation with the intermittent movement of the support to raise said web-embracing elements at the end of a feeding movement of the support whereby the web is lifted off the pins and to lower said web-embracing elements at the beginning of a feeding movement of the support whereby the holes in the web are threaded on to the pins.

Conveniently the web-embracing elements comprise a stripper plate and a threader plate slidably mounted on the support and between which the web passes, the pins passing through

holes in the stripper plate and the threader plate having holes to receive the pins. The stripper plate and the threader plate may be rigidly connected together to slide as a unit on the support and may be spring-urged into the position in which they hold the web with its holes threaded on to the pins, the machine including an actuator which rises at the end of a feed stroke of the support to lift the stripper and threader plates relatively to the support and falls at the end of a return stroke of the support to permit descent of said plates under the action of their spring.

The invention is particularly applicable to apparatus for punching records in successive zones of a web of paper, and the invention also comprises apparatus of this kind including in combination punches for making record and marginal feed holes in the web, and mechanism of the form set forth above for feeding the web past the punches and wherein the feed pin support is operative to make a feed stroke while the punches are out of engagement with the web and to make a return stroke while the punches are through the web, said apparatus also including mechanism, operative under the control of the punch actuating means, to effect the disengagement of the feed holes in the web from the pins as the punches penetrate the web and to effect the engagement of the feed holes with the pins during disengagement of the punches from the web.

Preferably such punching apparatus comprises settable punches for making record holes in the web, a pair of fixed punches for making marginal feed holes in the web, movable dies with which all said punches co-operate, mechanism for lifting the dies to effect punching while the feed pin support is at rest at the end of its return stroke and for lowering said dies to disengage the web from the punches while the support is at rest at the end of its feed stroke, and a pair of arms extending below the stripper plate and movable with said dies whereby on the rise of the dies to effect punching said arms raise the stripper and threader plates to lift the web off the feed pins and on the descent of the dies said arms are lowered away from the stripper plate, thereby permitting the stripper and threader plates to descend under spring action to thread the holes in the web onto the pins.

According to a further feature of the invention punching apparatus having the features set forth above includes an auxiliary feeding device located between the punches and a storage roll

for the web, and mechanism for actuating said auxiliary feeding device in timed relation with the operations of the feed pin support and of the punches in such a way that while the punches are through the web, the auxiliary feeding device draws from the storage roll sufficient of the web to form a bight, which is taken up during the feeding operation next performed by the feeding pins, whereby the feeding pins do not perform any work in unwinding the web from the storage roll and the web is thus free from appreciable tension during feeding operations.

Preferably the auxiliary feeding device includes a bar disposed parallel to the storage roll axis and arranged between the roll and the punches and mechanism is provided for lowering said bar on to the web to form the bight between the punches and the roll in between each feeding operation.

In order that the invention may be more fully understood one embodiment thereof will now be described by way of example with reference to the accompanying diagrammatic drawings, which show the invention applied to a machine for punching record holes in a tape.

In the accompanying drawings:

Figure 1 is a front elevation of the machine with the feed pins and their support at the beginning of a feed stroke;

Figure 2 is a front elevation similar to that shown in Figure 1 but with the feed pins and their support at the beginning of an idle return stroke;

Figure 3 is a vertical section on the line III—III of Figures 2 and 5;

Figure 4 is a detail view showing the construction of the oscillating support for the feed pins viewed from the right in Figure 1;

Figure 5 is a rear elevation of the machine;

Figure 6 is a vertical section through a comb bar for guiding certain slides which serve to select the punches, and

Figure 7 is a view in section to a larger scale of the take-up roll mechanism for the tape.

In the construction shown in the drawings the machine comprises a base plate 1, a main vertical frame plate 2, secured to the base plate, a vertical bar 3, standing up behind the plate 2 and likewise secured to the base plate 1, and an overhanging horizontal bar 4 bolted to the top of the bar 3, and passing through a slot 4a, in the plate 2 (Figs. 3 and 5).

The machine also includes a vertically reciprocable die plate assembly comprising two vertical bars 5 which are slotted at their lower ends 6 (Figs. 1 and 2) to engage over guide blocks 7 loosely mounted on a shaft 8, journaled in the plate 2 and a bearing plate 8a.

The lower die plate 9 is fixed across the upper ends of the two vertical bars 5 and the upper die plate 10 is screwed to the lower die plate at its rear end, the two plates having lateral extensions 9a and 10a respectively, which extensions afford additional means for receiving a securing screw or pin 11 to maintain the two plates in the correct relative position. The die plates are made thicker at their rear ends so that a gap 12 is provided between them through which the tape can be fed.

Fixed to the upper face of the upper die plate 10 are four guide posts 13 which are received in holes in a guide plate 14 suspended from the overhanging bar 4 by means of a plate 15 having wings 17 (Figs. 2 and 3) at each end to which the plate 14 is attached.

Secured across the side faces of the bars 5 at their upper ends is the lower limb 18 of a horizontal U-shaped member of which the upper limb 19 is secured to two of the guide posts 13, whereby the upper and lower die plates are firmly secured together along their length from front to rear of the machine, while leaving the gap 12 between them open at the front to permit insertion of the tape as will presently be explained.

10 The punches 20 for making the record perforations in the tape are freely mounted in apertures in the upper die plate 10 and the guide plate 14 and are selected for operation by means of manually settable slides 21.

15 In the illustrated construction there are four punches in each column and the digits 0 to 9 are respectively represented by a code involving single holes, or combinations of holes in the same column. For example the digit 1 may be represented by a single hole in the 1 position, the digit 5 may be represented by two holes in the same column, one in the 1 position and the other in the 2 position, while the digit 9 may be represented by three holes in the same column located in the 2, 3 and 4 positions respectively.

20 Each of the punch selecting slides 21 carries a number of abutment lugs 22 and can be moved by hand along the corresponding column of punches to bring the abutment lugs over the punches which are to be set. In order to provide for the code punching, each slide carries several of the lugs 22, each positioned on the slide and having a length such that it will overlie the required punch or punches when the slide 25 is positioned in accordance with the digit corresponding to the lug in question.

25 The slides 21 are guided for longitudinal movement in two comb bars 23 which project from the frame plate 2, the slides being maintained in the slots of the comb bars by the underside of the over-hanging bar 4. The arrangement of the slides 21 forms no part of the present invention and any convenient known mechanism may be provided for retaining them in the set position. By way of example Fig. 2 of the accompanying drawings shows for this purpose a common detent bar 24 cooperating with detent teeth 25 in the upper edges of the slides, said detent bar depending from the free edge of a plate 26 pivoted on a cross spindle 27 and urged by a spring 28 to hold the detent bar 24 in engagement with the teeth 25. The spindle 27 is carried between the frame plate 2 and a plate 29 attached to the front ends of the comb bars 23 and of the bar 4.

30 Between the two comb bars 23 the lower edges of the slides 21 are supported against lateral bending by a comb bar comprising an angle plate of which the vertical portion 30 is fixed to the upper arm 19 of the U-shaped member already referred to while the horizontal portion 31 of the angle plate is formed with slots 32 (Fig. 6) to receive the lower edges of the slides 21 these slots being deep enough to permit passage of the abutment lugs 22. It will be noted that the comb bar 30—31 moves up and down with the die plates 9 and 10 and therefore moves relatively to the slides 21.

35 The paper tape T is of approximately the same width as one of the standard record cards used in controlling a tabulating machine and in the present construction is wide enough to accommodate twenty-one columns for the reception of data perforations. Accordingly there are twenty-

ty-one columns of punches 20 arranged side by side across the machine from front to rear.

The paper tape T to be perforated is drawn from a stock roll 33, passes under an auxiliary feeding bar 35, the operation of which will be described later, then over a fixed guide rod 36 and then between the punch die plates 9 and 10 to the main feeding device. After leaving the main feeding device the tape passes over and under fixed guide rods 37 and 38 and is wound on a take-up roll 39.

The main feeding device includes an oscillating support 40 for a pair of feeding pins 41 which engage marginal perforations in the tape, these perforations, in the construction now being described, being made conjointly with the data representing perforations. The means for making the marginal perforations will now be described.

Projecting downwardly from the fixed guide plate 14 which is disposed above the upper die plate are two feed hole punches 42, one at each end of said plate, these punches being disposed in flanking relation to the longitudinal rows of data perforating punches 20, and cooperating with corresponding holes in the lower die plate 9.

As the lower and upper die plates 9 and 10 rise at each cycle of the machine the tape T is lifted by the lower die plate 9 and is thereby perforated with a marginal feeding hole adjacent each of its edges. In the construction now being described the punches 42 which form these feeding holes are of square cross section so that the feeding holes themselves are square.

After the paper tape T leaves the punching mechanism, it passes to the main feeding device, which includes the support 40 for the two feeding pins 41 which are of square cross section to engage the square marginal holes in the tape.

The support comprises a flat plate member 40a attached to an oscillatable shaft 43 and a flat plate 40 attached to the plate 40a in a manner which will be described later, the feeding pins 41 being fixed to the plate 40 and projecting from the upper edge of this plate 40.

Also mounted on the plate 40 is a stripper bar 44 through which the pins 41 freely pass, this stripper bar being mounted for vertical reciprocation on the plate 40 and normally drawn to its lower position by a spring 45, in which position the upper ends of the feeding pins 41 project above the stripper bar 44.

Mounted above the plane of the tape T and immediately above the stripper bar 44 is a threadder plate 46 which comprises in effect a flange bent out from the lower edge of the upper arm 47 of a U-shaped member of which the lower arm 48 is attached to the stripper bar 44 (Fig. 4). The threadder plate 46 is formed with holes 49 through which the feeding pins 41 can pass and it will be observed that the provision of the U-shaped member 47-48 affords a gap 50 between the stripper bar 44 and threadder plate 46 through which the tape T can pass, this gap being moreover open at the front, as seen in Fig. 1, so that the tape can be inserted in the manner which will be explained later.

Since the threadder plate 46 and stripper bar 44 are thus connected together they can move as a unit up and down on the support plate 40 for the feeding pins 41.

Projecting horizontally from each of the vertical bars 5 of the lower die plate assembly are two lifting bars 51 which respectively extend

under the ends of the stripper bar 44. The operation of this part of the mechanism is as follows:

When the bars 5 rise to lift the die plates 9 and 10 the lifting bars 51 rise with them and lift the stripper bar 44 and the threadder plate 46 relatively to the support plate 40 against the action of the spring 45, the stripper bar 44 thereby lifts the paper off the pins 41. On the other hand when the frame bars 5 descend the lifting bars 51 descend with them and the spring 45 pulls the stripper bar 44 and threadder plate 46 downwardly relatively to the support plate 40. During this operation the threadder plate 46 pushes the paper tape T down so that the marginal holes already made in the paper at the preceding machine cycle, which holes, as will be explained later, are at this time in register with the feeding pins 41, are threaded on to the pins, the pins 41 being uncovered and caused to project above the stripper bar 44 by the descent of that bar 44 relatively to the plate 40 on which the pins 41 are fixed.

The timing of the oscillation of the support plate 40 and the reciprocation of the bars 5 carrying the die plates 9 and 10 and the lifting bars 51 is such that during a feeding stroke of the plate 40 the bars 5 and die plates 9 and 10 are down and plate 40 moves away from the punches 20 and 42, pulling the paper T with it. At the end of the feed stroke the plate 40 remains at rest while bars 5 and die plates 9 and 10 rise and punching is effected. At this moment, therefore, two marginal holes are formed in the tape T, one at each side thereof.

The rise of the bars 5 lifts the stripper bar 44 whereby the paper is lifted clear of the pins 41, thereby rendering the plate 40 free to perform an idle return stroke. (Fig. 2 position.)

During this idle return stroke the bars 5 and die plates 9 and 10 remain up, so that the punches 20 and 42 are through the tape T and prevent any movement thereof.

At the end of the return stroke the plate 40 remains stationary while the bars 5 and die plates 9 and 10 descend. During the descent of the bars 5 the lifting bars 51 move down with it away from the stripper bar 44 and threadder plate 46, which under the action of their spring 45 descend relatively to the plate 40, whereby the threadder plate 46 pushes the paper T down and threads on to the pins 41 the holes which were made in the paper at the preceding punching operation. (Fig. 1 position.)

It may here be pointed out that since the punching of the feed holes is effected when the plate 40 is at the end of a feed stroke (Figure 2 position) the distance between successively punched feed holes must always be equal to the extent of movement of the feeding pins 41, whereby also when the plate 40 reaches the end of the return stroke (Figure 1 position) the pins 41 will be accurately disposed below the feed holes punched at the preceding operation, since the immediately preceding feeding operation has advanced these holes from the punches 42 by a distance equal to the spacing between the holes and therefore equal to the movement of the plate 40 and the pins 41 during the feeding stroke.

It will also be understood that since the data representing perforations are made conjointly with the feeding holes, there is no possibility of the data perforations becoming out of register with the feeding holes, as may be the case where the paper is formed with the feeding holes in one machine and the data perforations are made

in another machine through which the paper is fed by means of the feeding holes.

Since the lifting bars 51 extend underneath the stripper bar 44 throughout the entire path of its oscillating travel the upper surfaces of the lifting bars 51 are made arcuate as at 51a and of the same radius as the radius of the path of travel of the lower surface of the stripper bar 44 which engages with them, whereby the movement of the stripper bar is not impeded by the lifting bars.

Disposed between the stock roll 33 and the punching mechanism is an auxiliary feeding device comprising the bar 35 already referred to, which projects from one arm 52 of an actuating lever 52-60, transversely across the tape T, the lever 52-60 being fixed to shaft 43 which is rocked by mechanism to be described later in such a way that the bar 35 is rocked up and down in an arc running transversely of the path of travel of the tape.

The other arm 60 of the lever 52-60 actuates the take-up roll as will be described later, so that the take-up roll and the auxiliary feeding bar 35 are operated simultaneously.

As the lever 60-52 is fixed to the shaft 43, to which also the feed pin support 40 is fixed, the timing of the movement of this lever and therefore of the movement of the auxiliary feeding bar 35 is such that it moves downwardly (to the Figure 1 position) during a return stroke of the feed pin support 40 and upwardly (to the Figure 2 position) during the feed stroke.

As already explained during the return stroke of the feed pin support 40 the punches 20 and 42 are projecting through the paper, which therefore cannot move. During the return stroke the auxiliary feed bar 35 moves down to the Figure 1 position and since the paper cannot move by reason of the punches being in engagement with the holes which they have punched in it, the auxiliary feed bar 35 pulls a length of paper from the stock roll 33, which paper forms a loop or bight B between the stock roll and the punching mechanism.

During the descent of the punch dies 9 and 10 the auxiliary feeding bar 35 remains in its lowest (Figure 1) position, holding the loop or bight B of paper extended.

As the feed pin support 40 commences to execute the feed stroke so the auxiliary bar 35 commences to rise to the Figure 2 position. The feeding pins 41, during the feed stroke pull the paper tape T through the punches thereby taking up the bight B in the paper, but as the rise of the auxiliary feeding bar 35 takes place at a rate proportional to the rate of feed, the taking up of the bight is controlled so that at no time is the bight left completely loose, although the control is such as not to interfere with the taking up of the bight or to impose a load on the paper. At the end of the feed stroke the bar 35 has just reached the Figure 2 position.

By this means the feeding pins 41, in pulling the paper through the punches, only have to pull a short length of paper and do not have to do any work in unwinding paper from the stock roll 33 and turning the stock roll round. The stock roll remains stationary during the feeding movement of the paper and only moves at times when the paper is not being fed, this movement of the stock roll being effected by means of the auxiliary feeding bar 35 which pulls the requisite length of paper from the stock roll in readiness for feeding by the feeding pins 41.

After leaving the feeding device the tape T is passed over a fixed guide rod 37 and then under another fixed guide rod 38 whence it passes to the take-up roll indicated generally at 39. The take-up roll comprises a spindle 53 (Figure 7) projecting from the plate 2 and having freely mounted thereon a rotatable sleeve 54, held in place by a collar 55 fixed to the spindle 53. At its rear end the sleeve 54 carries a disc 56 on which is pivoted a pawl 57 co-operating with a ratchet wheel 58 freely mounted on the rear end of the spindle 53 and meshing with a rack 59 which is pivoted at its lower end to the arm 60 of the lever 52-60 and is held in engagement with the wheel 58 by a roll 61 mounted on a stud secured to the plate 2.

During the idle return stroke of the feed pin support plate 40 the rack is raised to rotate the wheel 58 clockwise in Figure 1, and the wheel, through the pawl 57 and disc 56 turns the sleeve 54 to wind up the tape, which is attached to the sleeve. During the feed stroke of the plate 40 the rack 59 descends and the wheel 58 rotates counterclockwise, the pawl slipping over the teeth thereof so that no movement is imparted to the sleeve 54.

In order to attach the tape to the sleeve 54, the free end of the tape is wound round a split sleeve (not shown) and held thereon by a tubular spring clip. The split sleeve is then pushed on to the sleeve 54 endwise, the springiness of the split sleeve affording sufficient grip to cause rotation of the sleeve 54 to wind up the tape.

It will be seen that during the feeding of the tape the take up sleeve 54 remains stationary and therefore the length of perforated paper which has been fed by the feeding pins 41 forms a loop or bight C (Figure 2) in advance of the take up sleeve 54. Then during the return stroke of the feeding pins, while the paper is stationary in the punching mechanism the sleeve 54 rotates to take up the bight C of paper. Thus the pull on the paper is reduced to a minimum, and since the free end of the tape is attached to the sleeve 54 only by the frictional grip of the split sleeve above referred to, no tearing of the paper can result.

From the foregoing it will be seen that the tape is not subjected to any strain due either to its unwinding from the stock roll 33 or to the action of the take-up roll in winding up the paper after it has been perforated.

In order to permit insertion of the tape into the machine means is provided for depressing the feeding pins 41 below the path of the tape. It will be understood that at the time when the tape is lifted clear of the pins 41 by the rise of the stripper bar 44 the punches 20 and 42 are through the tape so that although the tape is free so far as the feeding pins are concerned, the punches prevent the tape from being inserted or withdrawn.

Accordingly the support plate 40 to which the feeding pins 41 are rigidly attached is made in two parts of which one 40a is attached to the shaft 43 while the other part 40 is mounted to slide on the part 40a by means of pins and slots 40b and carries the pins 41. A manually operable control slide 62 is provided which is formed with slots 63 engaging pins 64 on the part 40a and with cam slots 65 engaging pins 66 on the part 40. By pushing the slide 62 in towards the rear of the machine by means of the finger piece 62a the cam slot pulls the part 40 with the feed pins 41 downwardly.

In order to insert the paper the machine is turned until the feed pin support is at rest at the end of its return stroke (Figure 1) and the bars 5 have descended to lower the die plates so that the punches do not project into the space 12 between them. The lowering of the bars 5 will have permitted the stripper bar and threader plate to descend under the action of their spring 45 so that the feed pins 41 will be projecting above the stripper bar 44 and into the holes 49 in the threader plate 46. The slide 62 is now pushed in rearwardly whereby the part 40 together with the pins 41 is drawn downwardly. During this operation the stripper bar 44 is held up by the lifting bars 51 and the stripper bar is thus prevented from following the downward movement of the pins 41 which in effect descend into the stripper bar so that they no longer project above it and consequently the space 12 between the die plates is clear for the insertion of the tape edgewise, from the front of the machine.

In order to prevent the tape from wandering laterally on the take up roll the outer end of the spindle 53 is made hollow as indicated at 61 (Figure 7) and a retaining finger 68 is pivoted on a pin 69 in a slot 10 formed in the extreme end of the spindle. Within the hollow portion 61 of the spindle 53 is mounted a plunger 71 urged outwardly by a spring 72, and the finger 68 is formed with a cam projection 73 extending on the other side of its pivot 69, and engaging with the plunger 71 at a point slightly off the centre of the pivot 69. By this means the spring 72 pushes the finger 68 lightly against the end face of the take up roll thereby preventing it from turning backwardly during the idle stroke of the rack 59.

In order to push the split sleeve carrying the free end of the tape on to the sleeve 54 the finger 68 is turned clockwise (Figure 7) so that it projects axially from the spindle 53 whereby the spring 72 is compressed. The split sleeve with the tape attached thereto is then pushed on endwise over the axially extending finger 68 on to the sleeve 54 after which the finger is turned back counter-clockwise to the position shown in Figure 7. After the finger has been thus turned to a certain position the spring loaded plunger 71 continues the movement and snaps the finger over until it stands at right angles to the axis of the spindle 53 in which position it bears against the outer surface of the roll of paper being wound on to the sleeve 54, thereby preventing the paper from wandering laterally.

A similar arrangement is provided for the stock-roll for the reception of which a fixed spindle 74 projecting from the plate 2 is provided. The end of this spindle is provided with a finger piece 68a pivoted in a slot in the end of the spindle and provided with a spring loaded plunger similar to the equivalent members associated with the take-up roll.

The operating mechanism of the machine is exceedingly simple and comprises a main shaft 15 to which are secured two cams 76 and 77 (Figure 5) of which one 76 operates the bars carrying the punch dies 9 and 10 and the lifting bars 51, while the other cam 77 operates the shaft 43 and thereby the feeding pin support 40, the auxiliary feed arm 35 and the rack 59 which actuates the take-up roll ratchet 58.

To this end the first mentioned cam 76 co-operates with the two rolls 78a on a follower lever 78, thus giving a positive operation in each direction. This lever is pivoted on a spindle 79

projecting rearwardly from the plate 2, the said lever 78 being connected by a link 80 to an arm 81 secured to the shaft 8. The bars 5 are connected by a transverse rod 82 on which are pivoted two depending connecting links 83, each of which is pivoted at its lower end by means of a rod 84 to a corresponding crank lug 85 formed integral with a casting 86 secured to the shaft 8. At each rotation of the main shaft 15 the first mentioned cam 76 rocks the die plate operating shaft 8 through the follower lever 78, the connecting link 80 and the arm 81 secured to said shaft 8, whereby the crank lugs 85 and connecting links 83 positively raise and lower the bars 5 and die plates 9 and 10.

The second mentioned cam 77 co-operates with a spring urged roll 81a on a follower lever 87 secured to the shaft 43 to which the lower part 40a of the feed pin support is secured so that as the main shaft rotates the feed pin support 40—40a is rocked in timed relationship with the operation of the die plates 9 and 10 in the manner already described.

Also secured to the shaft 43 is a lever 52—60, extending to either side of said shaft so as to be rocked therewith. One arm 52 of this lever carries the auxiliary feed bar 35 and the other arm 60 is pivoted to the rack 59 by means of which the take-up roll ratchet 58 is actuated.

A handle 89 is attached to the main shaft 15 for manual operation of the machine, but the machine may be driven by a motor if desired.

From the foregoing description it will be seen that the invention includes mechanism for feeding tape, strip, or web material from a storage roll past a device for operating on the web, and for winding the web on to a take up roll, including in combination feed pins adapted to engage feed holes in the web, means for moving the feed pins in one direction to feed the web and in the opposite direction to make an idle return stroke, means for engaging the web to hold it stationary during said idle return stroke of the pins, means for effecting relative movement between the web and the pins at each end of the stroke thereof so as to effect engagement of the feed holes with the pins at the beginning of the feed stroke and disengagement of the holes in the web from the pins at the end of the feed stroke, means for unwinding from the storage roll a length of web equal to the length to be fed, and means for actuating the take up roll and said unwinding means while the web is held stationary.

By this means the feed pins only feed a relatively short length of web at each feeding operation, the storage and take up rolls, with the bulk of the web remaining stationary during feeding operations performed by the feeding pins.

The invention further includes mechanism for feeding tape, strip or web record material through a device for punching record holes in the web, and for winding the punched web on to a take up roll, including in combination punches for making record and feed holes in the web, feed pins disposed to engage the feed holes and movable in one direction to feed the web while the punches are clear thereof and in the opposite direction to make an idle return stroke while the punches are through the web, means for moving the web relatively to the pins at each end of the stroke thereof so as to effect engagement of the feed holes in the web with the pins at the beginning of the feed stroke and disengagement of the holes from the pins at the end of the feed stroke, an auxiliary feeding bar, movable on to the portion

75

of the web between the punches and the storage roll, while the punches are through the web, to draw from the storage roll a length of web to form a bight equal to the length to be fed, said auxiliary feeding bar returning at a rate proportional to the rate of feed during each feed stroke of the feeding pins, whereby the taking up of the bight is controlled, and means for actuating the take up roll to wind up the punched web contemporaneously with the operation of the auxiliary feeding bar whereby the storage and take up rolls with the main bulk of the web are stationary during feeding operations of the feed pins, and while the feed pins are idle the main bulk of the web is fed by the action of the auxiliary feed bar and the take-up mechanism.

Accordingly the invention includes in combination means for feeding tape, strip or web record material intermittently and means operative in between successive intermittent feeding operations to unwind from the storage roll a length of the tape or strip equal to the length fed at each feeding operation, in readiness for feeding at the next operation of the feeding means, whereby during each feeding operation the storage roll remains stationary and the tape is freed, during feeding operations, from the tension which would be set up therein if the unwinding of the tape or web from the storage roll were effected by the feeding movement of said tape or web.

Accordingly the invention also includes a machine comprising in combination means for perforating data in a web, feeding pins or projections carried on a member adapted to oscillate in the path of feed of the web, means for making feeding perforations in the web contemporaneously with the making of the data perforations, and means for effecting relative movement between the feeding pins and the web at each end of the stroke of the carrier member, so as to effect engagement of the pins or projections with the feed holes in the web at the beginning of a feed stroke of the carrier, and disengagement of the pins or projections from said holes at the end of the feed stroke of the carrier.

It is to be understood that the invention also includes apparatus for punching records in successive zones of a sheet or web of paper comprising in combination punches for making a record and marginal feed holes in the paper, feed pins for feeding the paper past the punches, and means for moving the paper to thread the feed holes on to the pins after a punching operation and removing the paper from the pins before the next succeeding punching operation and means for actuating the feeding pins for a feeding operation while the feed holes are in engagement with the pins.

According to the present invention mechanism for feeding tape, strip or web record material, e. g. paper, through a statistical or like machine may comprise in combination feeding pins adapted to engage feeding holes in the tape or web, means for operating the feeding pins intermittently to feed the tape or web step by step, an auxiliary feeding device located between the tape storage roll and the feeding pins and means for actuating said auxiliary feeding device intermittently in such timed relationship with the intermittent operation of the feeding pins that, while the feeding pins are idle, the auxiliary feeding device draws from the storage roll sufficient of the tape or web to form a bight, which is taken up during the feeding operation next performed by the feeding pins, whereby the feeding pins do not

perform any work in unwinding the tape or web from the storage roll and the tape or web is thus free from appreciable tension during feeding operations.

5 I claim:

1. Mechanism for feeding a web of paper or the like through a punching machine, including in combination a movable punch member, an oscillatory support for feeding the web intermittently through the punch member, feed pins carried by said support, means on the support for moving the web relatively to the pins to effect engagement of the feed holes in the web with the pins at the beginning of a feed stroke of the support, and disengagement of the holes from the pins at the end of a feed stroke and said last named web moving means being controlled by the movable punch member.
2. In a machine for feeding a form through a member for operating on the form, in combination, means for reciprocating said member, an oscillating support for feeding the form intermittently through said member and means movably mounted along the longitudinal axis of the oscillating support and controlled by the movements of said member for moving the form into feeding and non-feeding relation with said oscillating support.
3. In a machine for feeding a form through a member for operating on the form, in combination, means for reciprocating said member, form feeding means including pins and an element on said feeding means for moving the form into attached and detached relation with the pins, means for oscillating the feeding means in feed and return strokes in timed relation with the reciprocations of said member and means controlled by the reciprocations of said member for actuating said form moving element at the end of each stroke of said feed means to attach the form to the pins for a feed stroke and detach the form from the pins for a return stroke.
4. In a mechanism for feeding a form from a supply roll to a take up roll and past a pin unit intermediate said rolls, in combination, means for reciprocating said unit to cause the pins thereof to engage the form, a feed member including feed pins and form engaging members, means for oscillating said feed member in feed and retract stroke sequence with the operation of said pin unit, and means on said unit for operating the form engaging member to move the form out of and in to feeding engagement with the feed pins when the pins of the unit are in and out of engagement with the form, respectively.
5. In a machine for feeding a form through a unit for operating on the form, in combination, means for reciprocating said unit, a feed member for advancing the form through the unit, means for intermittently actuating said feed member in feed and retract strokes between reciprocatory movements of said unit, and means controlled by the operation of said unit including members movably mounted on said feed member and presenting opposed form engaging surfaces for bringing the form into feeding and non-feeding relation with said feed member.
6. In a mechanism for feeding a form from a supply roll to a take up roll and past a pin unit intermediate said rolls, in combination, means for reciprocating said unit to cause the pins thereof to engage the form, a feed member including feed pins and a form engaging member, means for oscillating said feed member in feed and retract stroke sequence with the operation of said pin unit, and means on said unit for operating the form engaging member to move the form out of and in to feeding engagement with the feed pins when the pins of the unit are in and out of engagement with the form, respectively.

pin unit, means for operating the form engaging member to move the form into engagement with the feed pins for a feed stroke of said feed member while the pins of the unit are out of engagement with the form and said form engaging member being operable to move the form out of engagement with the feed pins for a retract stroke of the feed member while the pins of the unit are in engagement with the form.

7. In a machine for operating on a web of material used as a perforated form, in combination, a movable unit past which the web moves, means for feeding the web including a movable feed member, means for intermittently actuating the unit, means for moving the feed member in feed and retract strokes between movements of said unit, means movably mounted on said feed member and presenting opposed web engaging surfaces for bringing the web into feeding and non-feeding relation with said feeding member, and means on said unit for operating the web engaging means in synchronism with said feed member moving means.

8. In a machine for operating on a web of material used as a machine controlling form, spaced supply and take up rolls between which the web extends, means intermediate the rolls for operating on the web, means for intermittently producing an initial slack in the web between the supply roll and the operating means, means for drawing the web intermittently from the operating means to relocate said initial slack between said operating means and the take-up roll and means for actuating said take-up roll in coordination with the movement of said web drawing means to take up the slack in the web.

9. In a machine for perforating a web of paper or the like, spaced supply and take-up rolls between which the web extends, means intermediate the rolls for punching holes in the web, means for producing a slack in the web between the supply roll and the punch means equal to the amount of web to be fed, said slack being produced while the punch means is in punching engagement with the web, means for drawing the web intermittently from the punch means to relocate the slack between said punch and the take-up roll, and means for operating the take-up roll to absorb the relocated slack.

10. In a mechanism for feeding a perforated form from a supply roll to a take-up roll and past an intermediate unit for operating on the form, in combination, feed pins for engaging the perforations, means for moving the feed pins in one direction to feed the form and in the opposite direction to make an idle return stroke, said unit holding the form stationary during said return stroke, means on said pin moving means and movable with respect to said pins for effecting relative movement between the form and the pins at the end of each stroke to effect engagement of the pins with the perforations of the form at the beginning of a feed stroke and disengagement of the pins at the end of the feed stroke, means for unwinding a length of form from the supply roll equal to the amount to be fed, and means for alternately operating the take-up roll and the unwinding means while the form is stationary.

11. In a machine for operating on a perforated web or sheet of material used as a control form, in combination, a movable unit past which the web moves, means for feeding the web including feed pins for propelling engagement with perforations in said web, means on said web feeding means and operatively associated with said unit

for causing feeding and non-feeding engagement of said pins with the web, and means for actuating said web feeding means.

12. In a machine for feeding a form through a member for operating on the form, in combination, spaced supply and take-up rolls between which the form moves, spindles upon which the rolls are supported, means on said spindles for yieldable engagement with the edge of the form to prevent lateral wander thereof during winding, including a latch pivoted to the spindle and movable to a position in axial alignment therewith and to a position at right angles thereto and means for yieldably maintaining said latch in either of said positions and against the edge of the roll in the latter of said two positions.

13. Mechanism for feeding a web from a storage roll past a punch for perforating the web, and for winding the web onto a take up roll, including in combination, means for punching the web intermediate said rolls, feed pins adapted to engage holes punched in the web, means for moving the feed pins in one direction to feed the web away from the punching means and in the opposite direction to make an idle return stroke, the punch being arranged for engaging the web to hold it stationary during said idle return stroke of the pins, means for moving the web into and out of engagement with the pins at each end of the stroke thereof so as to effect engagement of the holes with the pins at the beginning of the feed stroke and disengagement of the holes in the web from the pins at the end of the feed stroke, means for unwinding from the storage roll a length of web equal to the length to be fed, and means operable in synchronism with said feed pin moving means for actuating the take-up roll and said unwinding means while the web is held stationary in the punch, whereby the feed pins only feed a relatively short length of web at each feeding operation, the storage and take up rolls with the bulk of the web remaining stationary during feeding operations performed by the feeding pins.

14. In a mechanism for feeding web material through a device for punching record holes in the web, and for winding the punched web onto a take up roll, the combination with punches for making record and feed holes in the web, of feed pins disposed to engage the feed holes and movable in one direction to feed the web while the punches are clear thereof and in the opposite direction to make an idle return stroke while the punches are through the web, means for moving the web relatively to the pins at each end of the stroke thereof so as to effect engagement of the feed holes in the web with the pins at the beginning of the feed stroke and disengagement of the holes from the pins at the end of the feed stroke, an auxiliary feeding bar engaging the web between the punches and the storage roll, while the punches are through the web, to draw from the storage roll a length of web to form a bight equal to the length to be fed, said auxiliary feeding bar returning at a rate proportional to the rate of feed during each feed stroke of the feeding pins, whereby the taking up of the bight is controlled, and means for actuating the take up roll to wind up the punched web contemporaneously with the operation of the auxiliary feeding bar whereby the storage and take up rolls with the main bulk of the web are stationary during feeding operations of the feed pins, and while the feed pins are idle the main bulk of the web is fed by the action of the auxiliary feed bar and the take-up mechanism.

15. In an apparatus for feeding web material from a storage roll through a machine, including web punching means, in combination, means for feeding the record material intermittently past the punching means and means including a rockable bar operative in between successive intermittent feeding operations and while the web is held by the punch to unwind from the storage roll a length of the tape or web equal to the length fed at each feeding operation, in readiness for feeding at the next operation of the feeding means, whereby during each feeding operation the storage roll remains stationary and the tape is freed, during feeding operations, from the tension which would be set up therein if the unwinding of the tape or web from the storage roll were effected by the feeding movement of said tape or web.

16. In a machine for perforating a web, punch means, a web feed member pivoted for swinging movement to feed the web past the punch, means for moving the web into and out of detached relation with the feed member, means for swinging said feed member, said swinging means and said web moving means operating in synchronism to attach the punched portion of the web to the feed member for a feed stroke of the latter and detach it from the feed member for a return stroke of the latter, and means operable in unison with the swinging movements of said feed member to produce a slack in the unpunched portion of the web and take up the punched portion of the web advanced by the feed stroke of said member.

17. In a machine for punching records in successive zones of a sheet or web of paper comprising in combination a punch for making record and marginal feed holes in the paper, a feed pin carrying member for feeding the paper past the punches, means on said pin member and controlled by said punch for moving the paper onto and off of the pins in synchronism with the operation of said punch, and means for actuating the feed pin member to feed the paper while the feed holes are in engagement with the pins.

18. Mechanism for feeding web record material in web form, through a statistical or like machine comprising in combination feeding pins adapted to engage feeding holes in the web, means for operating the feeding pins intermittently to feed the web step by step, a web feeding bar located between a web storage roll and the feeding pins and means for actuating said feeding bar intermittently in such timed relationship with the intermittent operation of the feeding pins that, while the feeding pins are idle, the feeding bar draws from the storage roll sufficient of the web to form a bight, which is taken up during the feeding operation next performed by the feeding pins, whereby the feeding pins do not perform any work in unwinding the web from the storage roll

5 and the web is thus free from appreciable tension during feeding operations.

19. In a mechanism for feeding a form of web tape from a supply roll to a take-up roll and past a unit intermediate said rolls for intermittent engagement with said form, in combination, a feed member for intermittently engaging and drawing the form a predetermined distance from said unit when the latter is disengaged from said form, an auxiliary feed means, means for operating said feed member and said auxiliary feed means in timed relation, and said auxiliary feed means being adapted to draw from said supply roll during engagement of the unit with the form a length of the latter equal to the amount thereof drawn from the unit by said feed member, and means controlled by said auxiliary feed means for operating the take-up roll to reel in the length of the form drawn from the unit by said feed member.

20. In a machine for perforating data in a web of paper or the like, movable means for punching holes in the web, web holding rolls between which the web passes to be engaged by said punching means, an oscillating support for feeding the web intermittently through the punching means, means movably mounted on said oscillating support and controlled by the movements of said punching means for moving the web into feeding and non-feeding relation with said oscillating support and means for drawing the web from one roll and winding it on another in timed relation with the oscillatory movements of said support.

21. In a mechanism for feeding a form through a punching unit, in combination, a member for pulling the form past the punching unit including pins for engagement with the holes of the form after the latter passes through said punching unit, means for oscillating said feeding member predetermined distances in feed and idle strokes, and means on said feeding member and movable longitudinally of the pins for causing engagement of said pins with the perforations of said form between the idle and feed strokes whereby the distance between perforations made in successive punching operations of the punching unit is accurately maintained by the successive feed movements of said feed member.

22. In a machine for feeding a form through a member for operating on the form, in combination, means for reciprocating said member, an oscillating support for feeding the form intermittently through the member including form engaging feed pins, means movably mounted on said oscillating support and controlled by the movements of said operating member for moving the form into feeding and non-feeding relation with said feed pins, and manual means for disabling the pins as a form engaging medium.

ARTHUR THOMAS.
